VALVE RESEATING TOOL

Bruce H. Black, Gary, Ind.

Application August 13, 1945, Serial No. 610,609

6 Claims. (Cl. 90—12.5)

This invention relates to a valve reseating tool and more particularly to such a tool for reseating the seats of gate valves. After such valves have been in use for a period of time, the seats become worn and it is necessary to cut new seats in order to prevent the valves from being scrapped. Various types of tools have been developed for this purpose, but those in general use are rather complicated and require considerable time to perform the reseating operation. Some types also require a series of units to fit various sizes of valves.

It is therefore an object of my invention to provide a simple and inexpensive valve reseating tool which can quickly and accurately perform the reseating operation.

This and other objects will be more apparent after referring to the following specification and attached drawings, in which:

Figure 1 is a cross sectional view showing the tool in position for machining a valve seat;

Figure 2 is a sectional view taken on line II—II of Figure 1;

Figure 3 is a sectional view taken on line III—III of Figure 1;

Figure 4 is an end view of the cutter;

Figure 5 is a view showing the profile of the teeth;

Figure 6 is a fragmentary cross sectional view similar to Figure 1 showing a second embodiment of the invention; and

Figure 7 is a fragmentary cross section showing a third embodiment of the invention.

Referring more particularly to the drawings, the reference numeral 2 indicates the body of a gate valve which has valve seats 4 and 6 to be recut. An axial opening 8 extends from valve seat 4 to the outside of the valve body 2 and is provided with the usual threads 10. A similar opening 12, having threads 14, extends from the valve seat 6 to the outside of the valve body. The tool consists of a cutter 16 which is similar to an end milling cutter and, as shown in Figures 4 and 5, is provided with teeth 18 around its periphery on one side thereof and a square opening 20 therein on the same side as the teeth 18. A rotatable shaft 22 is detachably connected to cutter 16 by means of a square end 24 which extends into opening 20. The shaft 22 may be rotated by any well known manual or power means. The hub portion 26 of the tool is provided with a threaded opening 28 therein for receiving a handle 30 which is long enough to extend out of the valve housing 2 when the valve stem and associated mechanism is removed. On

the side opposite the teeth 18, the cutter 16 is provided with a spherical seat 32. A feed screw 34 extends from the outside of valve body 2 through the opening 12 and is provided with a spherical end 36 which engages the spherical seat 32. The other end of the feed screw 34 is provided with a reduced square portion 38 for receiving a hand wheel 40 which is held in place by means of a screw 42 screwed into a threaded opening 44 at the end of shaft 34. Surrounding the feed screw 34 is an inner bushing 46 which has an eccentric threaded opening 48 therethrough for receiving the feed screw 34. The bushing 46 is provided with flat portions 50 for receiving a wrench or similar tool to rotate the bushing. The outer end of bushing 46 is provided with slots 52 and 54 for a purpose which will appear later. The bushing 46 is threaded into the eccentric opening 56 of an outer bushing 58 which is threaded into the threaded opening 14 of valve body 2. The bushing 58 is provided with a handle 59 to facilitate turning thereof. A lock nut 60, having a handle 62 is threaded onto the bushing 58 and a lock nut 64 having a handle 66 is threaded onto the bushing 46. A choke nut 68, having a handle 70, is threaded on that portion of the bushing 46 having slots 52 and 54 therein.

The operation of the device is as follows: When it is desired to machine seat 4, the cutter 16 is positioned on the valve seat and held in place by means of handle 30. Outer bushing 58 is screwed into the threads 14 with the lock nut 60 in place. Inner bushing 46 with nuts 64 and 68 in place is screwed into bushing 58 and feed screw 34 is screwed into bushing 46. The valve seats 4 and 6 are at an angle to the center line of the valve stem and the axial center line 72 of the valve, so that the cutter 16, when bearing on the seat 4, will be at the same angle. To function properly, the center of the cutter 16 should coincide with the center 74 of the seat 4. Since the cutter 16 sits at an angle, its center line 16 will not coincide with the valve center line 72. The thrust of the cutter 16 should be normal to the seat 4 along the center line 76 and to accomplish this the spherical end 36 of the feed screw is seated in the spherical seat 32 of the cutter with the common center of curvature 78 at the point of intersection of the feed screw center line 80 and the cutter center line 76. When the cutter 16 is centered on the seat 4 as indicated by the point 74, it will be noted that the center line 80 of the feed screw 34 is eccentric in relation to the valve center line 72.

For the purpose of centering the cutter, it is necessary to provide means for adjusting the eccentricity 82 of the feed screw in relation to the valve center line 72. This is done by combining the relative rotations of the eccentric bushings 46 and 58. The bushing 58 is easily turned to its desired position by means of its handle 59 and bushing 46 is turned by means of a wrench engaging the flat portions 50. With the eccentricity 82 set as desired, the lock nut 60 is tightened against housing 2 and lock nut 64 is tightened against bushing 58, thus locking the bushings in position to maintain the desired eccentricity 82. The feed screw 34 is advanced by means of the hand wheel 40 to maintain pressure of the cutter 16 on the seat 4. Slots 52 and 54 permit springiness of the end of bushing 46 so that when the choke nut 68 is screwed onto the thread of the bushing, it will grip the feed screw 34 and prevent it from turning when it is exerting the desired pressure on the cutter. The handle 30 is removed and the rotatable shaft 22 inserted into the socket 28 of the cutter 16 and the shaft rotated to machine the seat 4. When more pressure is desired on the cutter, the nut 68 is loosened and the feed screw 34 rotated to move it inwardly. If desired, the pressure exerted on screw 34 by means of nut 68 may be regulated to permit turning by hand wheel 40, but not by vibration or rotation of the cutter. After seat 4 is machined, the reseating tool is removed and repositioned with the cutter 16 bearing against valve seat 6, which is then machined in the same manner as described above for valve seat 4.

Figure 6 shows a modification of my invention for use in small valves. This modification is the same as that shown in Figure 1 except that only one eccentric bushing is used to center the cutter 16 on the seat 4 and a lock nut 84, having a handle 86, is provided to prevent turning of feed screw 34 in place of the slots 52 and 54 and choke nut 68. The feed screw 34 is received directly in the eccentric threaded opening 56 of bushing 58 and the device and operation thereof is otherwise the same as the first embodiment.

Figure 7 shows a third embodiment of the invention which is suitable for use with a flange gate valve. In this embodiment the valve body 2 is provided with flanges 88 having openings 90 therethrough. A flange 92, having openings 94 spaced in the same manner as openings 90, is fastened to the flange 88 by means of bolts and nuts 96 passing through the openings 90 and 94. The flange 92 has a threaded opening 98 therethrough for receiving bushing 58. In other words, the bushing 58, instead of being threaded into the threaded opening of the valve body 2, is threaded into the threaded opening 98. Otherwise, the device and its operation is the same as that disclosed in Figure 1.

While three embodiments of my invention have been shown and described, it will be apparent that other adaptations and modifications may be made without departing from the scope of the following claims.

I claim:

1. A tool for reseating a gate valve which has a threaded axial opening extending from each valve seat to the outside of the valve comprising a cutter, a rotatable shaft detachably connected to said cutter and extending through the opening adjacent the seat being cut, a spherical seat in the cutter on the side opposite the rotatable shaft, a feed screw, said feed screw having a spherical end for engaging the spherical seat of the cutter with

5 the center of curvature of the spherical seat being at the point of intersection of the feed screw center line and the cutter center line, a bushing having a threaded opening therein for receiving the feed screw, and means for supporting the bushing with the feed screw extending into the axial opening in the valve on the side remote from the seat being cut.

2. A tool for reseating a gate valve which has a threaded axial opening extending from each valve seat to the outside of the valve comprising a cutter, a rotatable shaft detachably connected to said cutter and extending through the opening adjacent the seat being cut, a spherical seat in the cutter on the side opposite the rotatable shaft, a feed screw, said feed screw having a spherical end for engaging the spherical seat of the cutter with the center of curvature of the spherical seat being at the point of intersection of the feed screw center line and the cutter center line, a bushing having an eccentric threaded opening therein for receiving said feed screw, and means for supporting the bushing with the feed screw extending into the axial opening in the valve on the side remote from the seat being cut.

3. A tool for reseating a gate valve which has a threaded axial opening extending from each valve seat to the outside of the valve comprising a cutter, a rotatable shaft detachably connected to said cutter and extending through the opening adjacent the seat being cut, a spherical seat in the cutter on the side opposite the rotatable shaft, a feed screw, said feed screw having a spherical end for engaging the spherical seat of the cutter, a bushing having an eccentric threaded opening therein for receiving said feed screw, a second bushing having an eccentric threaded opening therein for receiving the first bushing, and means for supporting the second bushing with the feed screw extending into the axial opening in the valve on the side remote from the seat being cut.

4. A tool for reseating a gate valve which has a threaded axial opening extending from each valve seat to the outside of the valve comprising a cutter, said cutter having a non-circular opening therein on the side adjacent the seat to be cut, a rotatable shaft having its end shaped to be received in said non-circular opening, a spherical seat in the cutter on the side opposite the non-circular opening, a feed screw, said feed screw having a spherical end for engaging the spherical seat of the cutter, a bushing having an eccentric threaded opening therein for receiving said feed screw, and a second bushing supported in the threaded axial opening in the valve on the side remote from the seat being cut, said second bushing having an eccentric threaded opening therein for receiving the first bushing.

5. A tool for reseating a gate valve which has a threaded axial opening extending from each valve seat to the outside of the valve comprising a cutter, said cutter having a non-circular opening therein on the side adjacent the seat to be cut, a rotatable shaft having its end shaped to be received in said non-circular opening, a spherical seat in the cutter on the side opposite the non-circular opening, a feed screw, said feed screw having a spherical end for engaging the spherical seat of the cutter with the center of curvature of the spherical seat being at the point of intersection of the feed screw center line and the cutter center line, a bushing having a threaded opening therein for receiving the feed screw, and means for supporting the bushing with the feed screw extending into the axial opening in the valve on the side remote from the seat being cut.

valve on the side remote from the seat being cut.

6. A tool for reseating a gate valve which has a threaded axial opening extending from each valve seat to the outside of the valve comprising a cutter, said cutter having a non-circular opening therein on the side adjacent the seat to be cut, a rotatable shaft having its end shaped to be received in said non-circular opening, a spherical seat in the cutter on the side opposite the non-circular opening, a feed screw, said feed screw having a spherical end for engaging the spherical seat of the cutter, a bushing having an eccentric threaded opening therein for receiving said feed screw, a second bushing having an eccentric threaded opening therein for receiving the first bushing, and means for supporting the second bushing with the feed screw extending into the

axial opening in the valve on the side remote from the seat being cut.
